INVENTOR.

John W. Myers
BY George C. Heinrichs

ATTORNEY.

UNITED STATES PATENT OFFICE.

JOHN W. MYERS, OF QUINCY, ILLINOIS.

VENTILATING MEANS FOR CHICKEN HOVERS AND BROODERS.

Application filed December 30, 1919. Serial No. 343,344.

To all whom it may concern:

Be it known that I, JOHN W. MYERS, a citizen of the United States, residing at Quincy, county of Adams, and State of Illinois, have invented certain new and useful Improvements in Ventilating Means for Chicken Hovers and Brooders, of which the following is a specification.

This invention relates to improvements in chicken hovers, particularly to the ventilating means therefor, and it is the principal object of the invention to provide a hover permitting the exhaust of the foul hot air at the top without creating a dangerous draft which is apt to injure the chickens.

Another object of the invention is the provision of a novel ventilator for hovers closed on top and bottom which is of a simple and inexpensive construction, allowing a ready application to a hover or removal therefrom, and which appears to produce an efficient ventilation without in any way endangering the lives of the chickens.

Other objects and advantages of my invention will become more fully known as the description thereof proceeds, and will then be specifically pointed out in the appended claim.

In the accompanying drawing forming a material part of my disclosure:

Figure 1 is an axial sectional view of a hover equipped with a ventilator constructed according to the present invention and adapted to be heated.

Figure 2 is a top plan view of the ventilator, and

Figure 3 is a section through the same on line 3—3 of Figure 2.

As here shown the body of the hover is made up of a conical housing 1 which may be of sheet metal and supported at a suitable distance above the ground by legs 2 formed of double metal straps riveted at

their ends to the housing 1. A circular 45 aperture is formed in the upper end of the housing and a ventilating member 3 fits snugly in said aperture. This ventilating member comprises a frusto-conical hollow casing having a peripheral rib 4 which rests 50 upon the top edge of the housing. A series of apertures 5 are formed in the casing below the rib and in communication with the interior of the casing, and a second series of apertures 6 are formed in the casing above 55 the rib and in communication with the outer air. The casing has a closed bottom and top, a handle 7 being secured to the latter whereby it may be lifted when desired.

Heating means for the hover are generally indicated at 8 and may be of any desired type supplied with fuel from any source of heat as for instance an oil burner or the like.

The operation of the device will be obvious from the above description thereof, the hot and foul air collecting under the roof of the hover will escape through the openings 5 and 6 in the ventilator and as the same is closed on top and bottom, no 70 draft will be created by the operation of the ventilator which would injure the chickens.

Having thus described my invention what I claim as new and desire to secure by Letters Patent, of the United States is as follows—

In a device of the character described, a roof with a circular opening in it, a ventilator comprising a frusto-conical hollow casing having an exterior encircling rib between the upper and lower ends thereof for supporting it in said opening, the side wall of said casing having openings formed therein above and below said rib, and a handle for said ventilator.

In testimony whereof I have affixed my signature.

JOHN W. MYERS.
